CLAIM

The ornamental design for a fender panel for truck hood, as shown and described.

DESCRIPTION

FIG. 1 is a front perspective view of a fender panel for truck hood showing a first embodiment of our new design;

FIG. 2 is a front elevational view of the fender panel for truck hood of FIG. 1;

FIG. 3 is a rear elevational view of the fender panel for truck hood of FIG. 1;

FIG. 4 is a top plan view of the fender panel for truck hood of FIG. 1;

FIG. 5 is a bottom plan view of the fender panel for truck hood of FIG. 1;

FIG. 6 is a right side elevational view of the fender panel for truck hood of FIG. 1, the left side elevational view of the fender panel for truck hood of FIG. 1 is unornamented;

FIG. 7 is a front perspective view of a fender panel for truck hood showing a second embodiment of our new design;

FIG. 8 is a front elevational view of a fender panel for truck hood of FIG. 7;

FIG. 9 is a rear elevational view of the fender panel for truck hood of FIG. 7;

FIG. 10 is a top plan view of the fender panel for truck hood of FIG. 7;

FIG. 11 is a bottom plan view of the fender panel for truck hood of FIG. 7;

FIG. 12 is a left side elevational view of the fender panel for truck hood of FIG. 7, the right side elevational view of the fender panel for truck hood of FIG. 7 is unornamented;

FIG. 13 is a front perspective view of a fender panel for truck hood showing a third embodiment of our new design;
FIG. 14 is a front elevational view of the fender panel for truck hood of FIG. 13;

FIG. 15 is a rear elevational view of the fender panel for truck hood of FIG. 13;

FIG. 16 is a top plan view of the fender panel for truck hood of FIG. 13;

FIG. 17 is a bottom plan view of the fender panel for truck hood of FIG. 13;

FIG. 18 is a right side elevational view of the fender panel for truck hood of FIG. 13, the left side elevational view of the fender panel for truck hood of FIG. 13 is unornamented;

FIG. 19 is a front perspective view of a fender panel for truck hood showing a fourth embodiment of our new design;

FIG. 20 is a front elevational view of the fender panel for truck hood of FIG. 19;

FIG. 21 is a rear elevational view of the fender panel for truck hood of FIG. 19;

FIG. 22 is a top plan view of the fender panel for truck hood of FIG. 19;

FIG. 23 is a bottom plan view of the fender panel for truck hood of FIG. 19; and,

FIG. 24 is a left side elevational view of the fender panel for truck hood of FIG. 19, the right side elevational view of the fender panel for truck hood of FIG. 19 is unornamented.

The broken lines in the drawings form no part of the claimed design.
